WILLIAM PARKIN, OF TAUNTON, MASSACHUSETTS, ASSIGNOR TO
REED AND BARTON, OF SAME PLACE.

Design No. 3,339, dated January 12, 1869.

DESIGN FOR A TEA-SERVICE.

The Schedule referred to in these Letters Patent and making part of the same.

all persons to whom these presents may come:

Be it known that I, WILLIAM PARKIN, of Taunton, in the county of Bristol, and State of Massachusetts, have invented or produced a new ornamental Design for a Tea-Service or Pot; and I do hereby declare the same to be fully described in the following specification, and represented in the accompanying drawing, or photographic representation, which denotes it in perspective elevation.

The engraved figures exhibited on the body-part of the design are not included in the design, which takes in the body of the vase, and the feet, the cover, and the handle thereof, formed in manner as represented.

In the drawings—

A denotes the vase;
B, the feet;
C, the cover; and
D, the handle.

The knob of the cover consists of a voluted scroll, and a lion-head and fore legs, resting on a base-plate.

The handle, in its general form, approximates to a trapezoid with rounded corners.

I claim the said design for a tea-service or pot, the same being substantially as represented and described.

WILLIAM PARKIN.
